UNITED STATES PATENT OFFICE.

WILLIAM M. SCOTT, OF PHILADELPHIA, PENNSYLVANIA, ASSIGNOR TO CUTTER ELECTRICAL AND MANUFACTURING COMPANY, A CORPORATION OF NEW JERSEY.

TIME-LIMIT CIRCUIT-BREAKER.

No. 839,079.

Specification of Letters Patent.

Patented Dec. 18, 1906.

Application filed February 17, 1903. Serial No. 143,771.

To all whom it may concern:

Be it known that I, WILLIAM M. SCOTT, a citizen of the United States, residing at Philadelphia, in the county of Philadelphia and 5 State of Pennsylvania, have invented a new and useful Time-Limit Circuit-Breaker, of which the following is a specification.

My invention relates to electrical switches, more particularly of the automatic magnetic 10 type employed for the protection of electrical apparatus from the effects resulting from undesired conditions in an electric circuit.

My invention consists of an automatic circuit-breaker whose function is to disrupt or 15 open an electric circuit upon the occurrence of predetermined conditions, such as under-load or overload in the circuit, or upon the occurrence of a predetermined potential difference on a circuit.

20 My invention consists of an automatic circuit-breaker so arranged and constructed as to open an electric circuit under predetermined conditions, but not until such conditions have obtained for a predetermined and 25 certain interval of time.

My invention consists of a time-limit circuit-breaker so arranged and constructed as to open an electric circuit after predetermined conditions have obtained for a definite 30 interval of time, and if such conditions disappear within such predetermined interval of time the parts return to their normal condition and position without having opened the circuit.

35 My invention consists also of further details in principle and construction, as herein-after described.

Reference is to be had to the accompanying drawings, in which—

40 Figure 1 is a side elevation of the circuit-breaker in circuit-closing position. Fig. 2 is a side view of the retarding element of the time device. Fig. 3 is an end view, partly in section, of the same. Fig. 4 is an enlarged 45 detailed view of the tripping apparatus of the circuit-breaker. Fig. 5 is a plan view of the tripping-magnet associated with one of the main terminal blocks. Fig. 6 is a front elevation of Fig. 5 on a reduced scale. Fig. 7 is 50 a sectional view on the line 7 7, Fig. 5. Fig. 8 is a plan view of the iron magnet. Fig. 9 is a section on the line 9 9, Fig. 8. Figs. 10 and 11 are fragmentary views illustrating the

means for adjusting the member 71. Fig. 12 is a view, principally diagrammatic, illustrating the electromagnet which actuates the tilting-chamber and its circuit connections. 55

A represents the base upon which the automatic circuit-breaker is mounted, of insulating material and generally a panel of a 60 switchboard.

1 and 2 are the main contact-terminals of the switch and consist of massive blocks of copper or other well-conducting material, having their contact-faces in practically the 65 same vertical plane. Circuit connections are made with the switch through the bolts or studs 3 and 4, which serve also to hold the main terminals 1 and 2 firmly against the switchboard A. 70

5 is a laminated movable contact member made up of numerous sheets of copper whose beveled ends engage with a resilient wiping contact upon the surface of the terminals 1 and 2. These laminae are secured to, but insulated from, the casting 6, which carries at 75 its lower extremity the roller 7, having a motion of translation in the slot 8, formed in a member secured to the base A.

9 is a reciprocating contact secured to the 80 base and which is engaged by the metallic spring-contact 10, which moves with the main laminated member 5, from which it is insulated, however. The casting or arm 6 has an upper extension 11, which rigidly 85 supports, though insulated from it, the upwardly-extending copper member 12, which is secured at its lower end to the arm 6, but insulated from said arm 6 and also from the laminated member 5. In the upper end of 90 this element 12 is a pivot 13, about which may rotate the shunt-carbon 14.

15 is the fixed shunt-carbon, pivoted at 16 to the upwardly-extending bracket 17, which is in electrical and mechanical communication with the main terminal 1. 95

19 is a metallic shunt-contact mechanically secured to and in electrical communication with the element 12.

20 is the fixed metallic shunt-contact with 100 which the contact 19 cooperates and is in electrical communication with the main terminal 1.

To operate the main laminated member 5 about its movable pivot 7, there is supplied 105 an operating-handle 21, pivoted at 22 in the

frame 23, secured to the base A. The operating-handle 21 extends beyond the pivot 22, such extension being represented at 24. 24 forms, in fact, one link of a toggle whose other link is 25, pivoted to the arm 6 at 26. 27 is the pivot common to both links 24 and 25. When the circuit-breaker is in the open position, the toggle is collapsed and the arm 21 raised above the position shown in Fig. 1. 10 To close the circuit-breaker, the operating-handle 21 is forced downwardly, this motion causing the straightening out of the toggle 24 25, with the consequent rotation of the laminated member 5 in a counter-clockwise direction about its pivot until it engages with the main terminals 1 and 2. The closing movement does not cease with the first contact between the member 5 and the main terminals 1 and 2, but is continued slightly thereafter, such continued motion bringing the pivots 22, 27, and 26 almost into a straight line and simultaneously springing the laminæ of the member 5, due to the pressure against the terminals 1 and 2. As this closing movement is completed the operating-handle 21 is locked in the position shown in Fig. 1 by a latch 28, which engages a roller 29 in an extension 30 integral with the operating member 21. Latch 28 therefore restrains the switch in a circuit-closing position.

During the closing movement the spiral springs 31 and 32 are put under tension, and so long as the circuit-breaker is in the circuit-closing position these springs remain under tension. Spring 31 connects at its left end with the pivoted arm 6 and at its right end with the pin 33 in the frame 23. Spring 32 is connected between the pin 33 and the extension 24 of the operating-handle 21. When the circuit-breaker has been tripped, spring 31 pulls the arm 6 toward the right, causing it to move with a motion of translation, due to the slot 8, and thereafter with a motion of rotation about its pivot 7, which has then passed to the right end of the slot 8. Simultaneously spring 32 pulls downwardly on the extension 24, thereby aiding in breaking the toggle, opening the switch, and raising the handle 21.

When the current through the circuit-breaker attains a predetermined value, the iron armature 34 is drawn upwardly by a magnet 34^a, depending for its strength upon the current flowing through the instrument. This magnet 34^a consists of a U-shaped piece of iron, as shown in Fig. 8. The inner wall of the circular portion is tapered, as clearly shown in Fig. 9. This tapered portion fits over a corresponding tapered portion of the main terminal block 2 and concentric with the stud 4. The disposition of this magnet with respect to the terminal block 2 is shown in Figs. 5, 6, and 7, from which it is seen that the iron of the magnet partially surrounds

the stud or terminal block and is surrounded by or embedded in the terminal block. The magnet is shown at 101 and has a wedge-shaped opening between its pole-pieces, between which a correspondingly-shaped armature may operate.

102 represents a depression in the terminal block to accommodate a bolt-head or nut of a bolt which may extend through the opening 103.

105 The armature 34 is secured to the end of the member 35 pivoted in the frame 23 at 36. Pivoted at 37 in the member 35 is a downwardly-extending link 38, pivoted at 39 in a horizontal member 40, which is pivoted 80 to the frame 23 at 41. Depending from the member 40 is a frame 42, having mounted in it the adjusting-screw 43, which when rotated will cause the weight 44 to be moved backwardly and forwardly. To prevent the 85 rotation of the weight 44 with the screw 43, the former is slotted and embraces with its slot the edge of the plate 45 mounted in the frame 42. Along this plate 45 are suitable calibration-marks, and by adjusting the 90 weight 44 to any desired calibration-mark the condition is determined at which the circuit-breaker will open. By shifting the position of the weight 44 to different points the amount of force that must be exerted by the 95 tripping-magnet on the armature 34 is varied.

46 is a bracket secured to the frame 23 and at its lower extension is provided with a hole 47, slightly larger than the pin 48, carried by the frame 40. This construction of pin and hole is a limiting device for the upward movement of the member 40. At the right end of the member 40 is secured the electrode or contact-piece 49, which is, however, insulated from the member 40.

50 is a fixed electrode coöperating with the electrode 49 and included in the circuit of an electromagnet having a single core, at the ends of which are secured by screws 51 the 110 iron cheeks or pole-pieces 52. Pivoted at 53 in said pole-pieces is the movable armature 54, which when the electromagnet is energized is attracted in a counter-clockwise direction.

52^a and 52^b are shunt magnet-windings disposed upon the horizontally-extending cores having pole-pieces 52. The windings 52^a and 52^b are included in a circuit extending from 52^c, one side of the main circuit, 120 through the winding 52^b, contacts 49 and 50, winding 52^a and contact 9, which coöperates with the spring-contact 10 adapted to be connected by a flexible conductor, as 10', with the contact-bridge 5 or either of the 125 main terminals 1 or 2, which are connected in the other main conductor 52^d.

Extending downwardly below the pole-pieces 52 are the brackets 55, between which is pivoted at 56 upon a horizontal pivot the 130

cylindrical chamber 57. On the same axis 56 is pivoted the triangular plate 58, which carries at its one corner the pivoted roller 59 and at the other corner the pin or roller 60, which is adapted to engage with one of the flanges 61 of the chamber 57 to limit the rotation of the plate 58 in a counter-clockwise direction. 62 is another flange of the chamber 57, said chamber being, in fact, in two portions, which are secured together by said flanges 61 and 62.

The armature 54 is provided with an extension beyond the pivot 53 (indicated at 63) and provided at its lower end with the horizontally-disposed cam-plate 64. A spring 65, joined at its one end to the member 63 and at its other end at 66 in a fixed portion of the instrument, tends to hold the armature 54 in its retracted position.

20 The chamber 57, as previously stated, is made up of two portions which are secured together by means of their flanges 61 and 62. The end walls of the chamber 67 and 68 extend laterally, and in their extremities is 25 mounted the screw 69, which may be turned by thumb-nut 70.

71 is a weight which is screw-threaded to receive 69 and slides along the guide-rod 72 and is prevented from rotating with screw 69 30 by said guide-rod 72. Turning the thumb-screw 70 changes the position of the center of gravity of the device with respect to the axis 56.

Pivoted within the chamber is the trap-door 73, pivoted at 74 and having one or 35 more small openings 75. The member 73 is of such dimensions and so disposed that it can never become perpendicular to the axis of the cylinder 57, but is always at some inclined position, as shown in Fig. 2. Its rotation, therefore, can proceed no farther than 40 shown in Fig. 2 in a clockwise direction, but its rotation in a counter-clockwise direction may be considerable, thereby allowing a relatively large gap between the lower edge of 45 member 73 and the lower internal surface of the cylinder 57. Within the cylinder 57 is placed a quantity of mercury or other suitable heavy liquid or mass, which, from its 50 weight and because of the disposition of the trap-door 73, normally maintains the cylinder 57 in the inclined position shown in Figs. 1 and 4. Upon tilting the cylinder 57 in a counter-clockwise direction, as viewed in 55 Fig. 1, the level of the mercury will rise to or above the holes 75 in the trap-door 73 and will flow through these restricted passages or orifices into the left-hand portion of the cylinder. If the cylinder 57 be tilted to such 60 position for a sufficient interval of time, enough mercury will have passed into the left end of the cylinder 57 to cause such cylinder to become heaviest at its left end and to rotate about its axis 56. The tilting of the 65 cylinder 57 is accomplished by the armature

54. When this armature 54 is attracted by its electromagnet, a cam-plate 64 presses downwardly on the roller 59, which transmits the force through the plate 58 to the cylinder 57, rotating it to a certain position, 70 where the mercury will be enabled to flow through the orifice 75 in the trap-door 73. If the armature 54 remains attracted sufficiently long, enough mercury will have found its way into the left-hand end of the cylinder 57, causing it to rotate voluntarily about its axis 56, such rotation being through a very considerable angle, as will be herein-after described.

The latch 28, heretofore referred to, is pivoted to a fixed portion of the instrument at 76. Mounted for rotation about this same pivot 76 is the member 77, joined to the latch 28 by the spring 78.

79 is a projection from the member 77, 85 which engages with a downward projection from the latch 28. The member 77 continues beyond the pivot 76 in a portion 80, between whose outer end and the bracket 46 is the spiral spring 81 which in the position 90 shown in Figs. 1 and 4 is under tension. In the extension 80 there is pivoted at 82 a toggle-link 83, at whose lower end is the pivotal connection 84 with the second toggle-link 85, pivoted in the bracket 46 at 86. The toggle 95 member 85 has a downwardly-extending portion at 87 and having a portion 88 extending approximately horizontally from the approximately vertical portion 87. The toggle 83 85 when extended as shown in Figs. 1 and 100 4 holds the member 77 in the position shown and maintains the spring 81 under tension.

When sufficient mercury has gotten into the left-hand compartment of the cylinder 57 by the process above described, such cylinder 57 rotates about its axis 56 through a great portion of a revolution until the upper right-hand portion of cylinder 57 strikes the outer end of the member 88. By this operation the cylinder 57 delivers a blow to the outer end of the member 88, causing the toggle member 85 to rotate in a clockwise direction about its pivot 86, thereby breaking the toggle and permitting the spring 81 to contract. In so contracting spring 81 operates 115 upon the extension 80, causing the member 77 to engage by its projection 79 with the latch 28, raising such latch and freeing the roller 29 from the latch 28. The roller 29 being disengaged from the latch 28, the circuit-breaker is opened, due in part to the springs 31 and 32 and in part to gravity.

89 is a vertically-reciprocating rods provided at its top with a roller 90 and intermediate its ends with longitudinal slots 91 and 92. These slots embrace pins 93 and 94, respectively, 93 being supported by the bracket 95, secured to the frame of the device, and pin 94 is supported by a member 96, also extending from the frame of the appara- 130

tus. Secured at its upper end to the bracket 95 is the spring 97, which is secured at its lower end, at 98, to the rod 89. This spring 97 therefore tends to keep the rod in its raised position. At the lower end of the rod 89 is a horizontally-disposed cam-plate 99, which is adapted to coöperate with the roller 100, secured to the movable chamber 57. The purpose of the rod 89, cam-surface 99, and roller 100 is to reset the chamber 57 to the position shown in Figs. 1 and 4 as soon as the circuit-breaker has opened the circuit. During the opening movement of the circuit-breaker the member 24 of the main toggle rotates in a counter-clockwise direction about its pivot 22, and its under surface acts as a cam pressing downwardly upon the roller 90, thus forcing the rod 89 and the cam-surface 99 downwardly. At the beginning of this downward motion of rod 89 the chamber 57 is not in the position shown in Figs. 1 and 4, but in its rotated position, as formerly described, and the roller 100 is therefore in a position considerably vertically above position shown in Fig. 4. The downward motion of rod 89 in consequence forces downwardly the roller 100, which results in the rotation of the chamber 57 in a clockwise direction, and when the rod 89 has completed its travel the chamber 57 has again assumed its position as shown in Fig. 4. The dotted position of the member 24, rod 89, and cam-plate 99 shows the state of affairs at the moment when the circuit-breaker has come to the end of its opening movement.

During the rotation of the chamber 57 in the clockwise direction during the resetting movement the mercury in the lower or left-hand compartment rushes back into the right-hand compartment under the edge of the trap-door 73, which permits of this rapid passage of the mercury because of its freedom to rotate about the pivot 74 in a direction suitable for the purpose, as seen in Fig. 2. Upon resetting or closing the circuit-breaker the member 24 rises, and so also does the rod 89 under the influence of spring 97, its upward movement being limited only by the slots 91 and 92 engaging at their lower ends with the pins 93 and 94. The cam-surface 99 then occupies the position shown in full lines in Fig. 4. The mercury in the chamber 57 having returned to the right-hand compartment, said chamber remains in the position shown at Fig. 4 in virtue of the cam-plate 64 being in the path of travel of the roller 59 on the plate 58.

The operation of the device is as follows: Supposing the circuit-breaker be required to open a circuit in the case of current of two thousand amperes (or more) flowing in the circuit for a period of ten seconds. The weight 44 is adjusted until some reference-mark comes opposite the graduation corresponding to two thousand amperes. The orifice or ori-

fices 75 in the trap-door 73 have already been calibrated, so that in ten seconds a stream of mercury will flow into the left-hand compartment of the chamber 58 to cause the chamber 57 to rotate about its axis 56 in a counter-clockwise direction to engage the member 88. Upon the current reaching the value of two thousand amperes the armature 34 is attracted upwardly, raising the arm or frame 40, which rotates about the pivot 41 and brings the electrodes 49 and 50 into engagement with each other, thereby energizing the electromagnet whose pole-pieces are shown at 52, and this results in the attraction of the armature 54. The upward travel of the arm 40, and therefore of the armature 34, is limited by the hole 47, which is slightly larger than the pin 48. The purpose of this construction is to prevent the armature 34 being attracted to a position so near its controlling-magnet that a current considerably less than two thousand amperes might retain it in its attracted position, and thereby maintain the circuit closed at contacts 49 and 50. In other words, this structure insures the separation of contacts 49 and 50 should the current fall below two thousand amperes at any time before the expiration of ten seconds. As soon as circuit is made between 49 and 50 the armature 54 is attracted and cam-plate 64 rotates the cylinder 57 into such position that the mercury begins to flow through the small orifices 75 in the trap-door 73. Now in case this current of two thousand amperes continues for ten seconds contacts 49 and 50 will be in engagement for ten seconds at least, armature 54 will remain attracted during the same period of time, and the chamber 57 will remain tilted during such period of time. At the expiration of ten seconds, however, enough mercury has flowed from the right-hand compartment of chamber 57 into the left-hand compartment to cause such chamber to rotate rapidly and forcibly about its pivot 56 and deliver a blow to the top side of member 88, as heretofore described. This operation causes the breaking of the toggle 83 85, the downward motion of the member 80 under the influence of the spring 81 resulting in the member 77 by its projection 79 lifting the latch 28 to release the roller 29, and thereby permitting the circuit-breaker to open. With the circuit-broken armature 34 is no longer attracted and in consequence the arm 40 falls, breaking circuit between 49 and 50.

The operation of resetting the circuit-breaker has been previously described, especially with reference to rod 89 in its operation resetting chamber 57. Suppose, however, that at the expiration of seven and a half seconds the current in the instrument falls below the critical value of two thousand amperes, the arm 40 drops downwardly again, breaking circuit between 49 and 50 be-

cause of the limited upward movement of the armature 34 in virtue of pin 48 and hole 47. With the circuit broken at 49 and 50 the armature 54 moves to its retracted position, as shown in Fig. 4, and the chamber 57 returns to its position shown in Fig. 4, and whatever mercury has passed into the left-hand compartment now returns quickly to the right-hand compartment under the 10 lower edge of the trap-door 73. The circuit-breaker is then again in precisely the same position as if the current had never attained the value of two thousand amperes—in other words, unless a predetermined current obtains for a predetermined time the circuit-breaker will not open, and if the predetermined current obtains for a time less than the predetermined time limit the circuit-breaker returns to its normal condition automatically. The location of the contacts 49 and 50 with reference to the field of the magnet whose armature is 54 is such that said magnet operates as a magnetic blow-out for any arcs bridging 49 and 50.

25 Though I have shown my improved tripping mechanism as applied to a circuit-breaker to be operated upon abnormally high-current conditions, it is to be understood that my invention is obviously adapted to 30 abnormally low-current conditions, predetermined high voltage, or predetermined low voltage. My tripping device may also be applied by any one skilled in the art to combined current and potential features known 35 as overload and underload switches, overload and reversal switches, or overload, underload, and reversal switches; in fact, to any type of electrical switch.

What I claim is—

40 1. In an automatic magnetic circuit-breaker, fixed terminals, a member adapted to bridge said terminals, a latch restraining said bridging member in normal position, an electromagnet in the circuit of said bridging member, a circuit controlled by said electromagnet, and a pivoted liquid-containing chamber having relatively large range of movement controlled by said circuit for delivering a blow to said latch a predetermined 45 interval of time after the closure of said circuit.

50 2. In an automatic circuit-breaker, fixed terminals, a movable contact member coöperating therewith, a latch for restraining said contact member in normal position, an electromagnet in the circuit of said terminals and contact member, a circuit controlled by said electromagnet, a chamber controlled by said circuit for actuating said latch, a movable 55 mass within said chamber, and means for retarding the passage of said mass from one portion of said chamber to another.

55 3. In an automatic circuit-breaker, fixed terminals, a movable contact member coöperating therewith, a latch restraining said

contact member in normal position, an electromagnet in the circuit of said terminals and contact member, a circuit controlled by said electromagnet, a chamber controlled by said circuit, a mass of liquid within said chamber, and means for restricting the passage of said liquid from one portion of said chamber to another. 70

4. In an automatic circuit-breaker, fixed terminals, a movable contact member coöperating therewith, a latch restraining said contact member in normal position, an electromagnet in the circuit of said terminals and contact member, a circuit controlled thereby, a magnet-winding included in said circuit, a 80 liquid mass operating as a trip actuated by said magnet, and means for preventing the operation of said mass for a definite interval of time. 75

5. In an automatic circuit-breaker, fixed terminals, a movable contact member coöperating therewith, a latch restraining said contact member in normal position, a latch-actuating device comprising a chamber having relatively large range of movement and 90 containing a mass of liquid, and electroresponsive means for controlling said latch-actuating device. 85

6. In an automatic circuit-breaker, fixed terminals, a movable contact member coöperating therewith, a latch restraining said contact member in normal position, a hammer for actuating said latch, and means controlled by the current passing through said contact member for starting said hammer, 95 said hammer comprising a chamber having a relatively large range of movement and containing a liquid restricted in its passage from one portion of said chamber to another. 100

7. In an automatic circuit-breaker, fixed terminals, a movable contact member coöperating therewith, a latch restraining said contact member in normal position, an electromagnet, a circuit controlled thereby, a hammer, and means controlled by said circuit for starting said hammer to deliver a blow to said latch, said hammer comprising a chamber having relatively great range of movement and containing a mass of liquid. 105 110

8. In an automatic circuit-breaker, fixed terminals, a movable contact member coöperating therewith, a latch restraining said contact member in normal position, means for actuating said latch, a toggle restraining said latch-actuating means in normal position, and a retarded hammer for breaking 115 said toggle. 120

9. In an automatic circuit-breaker, fixed terminals, a movable contact member coöperating therewith, means for restraining said contact member in normal position, means responsive to predetermined electrical conditions in a circuit, a hammer controlled thereby and comprising a chamber having large 125 range of movement and containing a mov- 130

- able mass, means in said chamber for retarding said movable mass, and means engaged by said hammer for controlling said restraining means.
10. In an automatic circuit-breaker, fixed terminals, a movable contact member coöperating therewith, a latch restraining said contact member in normal position, means for actuating said latch, a toggle restraining said latch-actuating means in normal position, electroresponsive means, and means controlled thereby for breaking said toggle after a predetermined interval of time.
11. In an automatic circuit-breaker, fixed terminals, a movable contact member coöperating therewith, a latch restraining said contact member in normal position, means for actuating said latch, a toggle restraining said latch-actuating means in normal position, electroresponsive means, a circuit controlled thereby, and means controlled by said circuit for breaking said toggle after a definite interval of time.
12. In an automatic circuit-breaker, fixed terminals, a movable contact member coöperating therewith, a latch restraining said contact member in normal position, a retarded hammer for actuating said latch, and means for restoring said hammer to normal position upon the opening of the circuit-breaker.
13. In an automatic circuit-breaker, fixed terminals, a movable contact member coöperating therewith, a latch restraining said contact member in normal position, a retarded hammer for actuating said latch, electroresponsive means for starting said hammer, and means for restoring said hammer to normal position after the actuation of said latch.
14. In an automatic circuit-breaker, fixed terminals, a movable contact member coöperating therewith, means restraining said contact member in normal position, a hammer, comprising a chamber having large range of movement and containing a retarded movable mass, for controlling said restraining means, means responsive to predetermined electrical conditions in a circuit, a circuit controlled thereby, and means controlled by said circuit for starting said hammer.
15. In an automatic circuit-breaker, fixed terminals, a movable contact member coöperating therewith, means restraining said contact member in normal position, a local circuit, a hammer, means responsive to abnormal current-flow for closing said local circuit, and means controlled by said circuit for starting said hammer for controlling said restraining means, said hammer comprising a chamber containing a movable mass and means for retarding the movement of said mass.
16. In an automatic circuit-breaker, fixed terminals, a movable contact member coöperating therewith, a toggle for operating said movable contact member, means for restraining said toggle in normal position, a chamber having large range of movement and containing a mass restricted in its movement for actuating said restraining means, and means responsive to predetermined electrical conditions in a circuit, for starting said chamber.
17. In an automatic circuit-breaker, fixed terminals, a movable contact member coöperating therewith, a toggle for operating said movable contact member, a latch restraining said toggle in extended position, means actuated by abnormal current-flow and a retarded mass of liquid having relatively large range of movement controlled thereby, for delivering a blow to said latch after a predetermined interval of time.
18. In an automatic circuit-breaker, fixed terminals, a movable contact member coöperating therewith, a latch restraining said contact member in normal position, a magnet, an armature therefor, means for preventing the near approach of said armature to said magnet, a retarded hammer for actuating said latch and means controlled by said armature for starting said hammer.
19. In an automatic circuit-breaker, separable coöperative contacts, a latch for restraining said contacts in normal position, and a pivoted liquid-containing chamber, having relatively great range of movement for delivering a blow to said latch.
20. In an electric switch, separable coöperative contacts, a latch for restraining said contacts in normal position, and a pivoted chamber having relatively great range of movement containing a liquid mass for delivering a blow to said latch.
21. In an automatic circuit-breaker, separable coöperative contacts, a latch for restraining said contacts in normal position, a tripping-magnet, and a liquid-containing chamber having relatively great range of movement for delivering a blow to said latch and controlled by said tripping-magnet.
22. In a tripping mechanism for electric switches, means for delivering a blow comprising a chamber, a liquid mass contained therein, and means for retarding the passage of said mass from one portion of the chamber to another portion.
23. In a tripping mechanism for electric switches, means for delivering a blow comprising a pivoted chamber, a liquid mass contained therein, and means for retarding the passage of said mass from one portion of said chamber to another portion thereof.
24. In a tripping mechanism for electric switches, a chamber, a liquid mass contained therein, means for retarding the passage of said mass from one portion of said chamber to another portion thereof, and means for permitting an unretarded return of said mass.
25. A tripping mechanism for electric

- switches, comprising a pivoted chamber, a liquid mass contained therein, means for retarding the passage of said mass from one portion of said chamber into another portion thereof, and electromagnetic means for initially tilting said chamber.
26. In a tripping mechanism for electric switches, a chamber, a movable mass contained therein, means for retarding the passage of said mass from one portion of said chamber to another portion thereof, and means permitting the unretarded return of said mass.
27. A tripping mechanism for electric switches, comprising a pivoted chamber, a movable mass contained therein, means for retarding the passage of said mass from one portion of said chamber to another portion thereof, and electromagnetic means for tilting said chamber.
28. A tripping mechanism for electric switches, comprising a pivoted chamber, a movable mass contained therein, means for retarding the passage of said mass from one portion of said chamber to another portion thereof, electromagnetic means for tilting said chamber, and means for returning said chamber to its normal position.
29. In combination, a terminal block, and a magnetizable mass forming an unclosed magnetic circuit embedded in said block.
30. In combination, a terminal block, a conductor leading thereto, and a magnetizable mass forming an unclosed magnetic circuit embedded in said terminal block and embracing said conductor.
31. In an electric switch, a base, a terminal block secured against said base, a conductor extending through said base and connecting with said terminal block, and a magnetizable mass located between said base and terminal block in a recess in said block.
32. In an electric switch, a base, a terminal block, a conductor extending through said base and connecting with said terminal block, and a magnetizable mass forming an unclosed magnetic circuit embedded in said terminal block between said base and terminal block, and embracing said conductor.
33. In an electric switch, a base, a massive terminal block secured thereto, a conductor extending through said base and communicating with said terminal block, and a magnetizable mass embedded in said terminal block, and maintained between said block and base and embracing said conductor, said magnetizable mass being substantially U-shaped.
34. In combination, a massive terminal block, a stud connected therewith, a depression in said terminal block surrounding the juncture of said stud and block, and a magnetizable mass forming an unclosed magnetic circuit seated in said depression.
35. In combination, a terminal block, and a magnetizable mass forming an unclosed magnetic circuit embedded in said terminal block and having pole-pieces extending beyond a surface of said terminal block.
36. In combination, a terminal block, a conductor joined thereto, and a magnetizable mass forming an unclosed magnetic circuit embedded in said terminal block and embracing said conductor, and having pole-pieces extending beyond the surface of said terminal block.
37. In an automatic circuit-breaker, fixed and movable contacts, means for restraining a movable contact in normal position, and means for actuating said restraining means after a predetermined interval of time, said means comprising a mass of liquid retarded in its flow in one direction and unretarded in return.
38. In an electric switch, a movable contact member, means for restraining said contact member in normal position, electroresponsive means, a subsidiary circuit controlled by said electroresponsive means, a chamber, a movable mass contained therein, electrically-actuated means included in said subsidiary circuit and adapted to tilt said chamber to cause the same to control said restraining means, means for retarding the movement of said movable mass in said chamber, and means for permitting the unretarded return of said movable mass.
39. In circuit-breaker-tripping mechanism, a time-limit device comprising a chamber, a movable mass within the chamber, means for retarding the passage of said mass in its passage in said chamber, and means permitting the unretarded return of said mass.
40. In circuit-breaker-tripping mechanism, a time-limit device comprising a pivoted chamber, a movable mass contained therein, means for initially tilting said chamber, means for retarding the passage of said movable mass from one part of said chamber to another when in tilted position, a latch actuated by said chamber an interval of time after it has been tilted, and means for permitting the unretarded return of said movable mass.

WM. M. SCOTT.
